UNITED STATES PATENT OFFICE.

BYERS W. KADEL, OF BALTIMORE, MARYLAND, ASSIGNOR, BY MESNE ASSIGNMENTS,
TO THE SYMINGTON COMPANY, A CORPORATION OF MARYLAND.

DRAFT YOKE.

Application filed July 20, 1920. Serial No. 397,714.

To all whom it may concern:

Be it known that I, BYERS W. KADEL, a citizen of the United States, residing at Baltimore, in the State of Maryland, have ⁵ invented certain new and useful Improvements in Draft Yokes; and I do hereby declare the following to be a full, clear, and exact description of the invention, such as will enable others skilled in the art to which ¹⁰ it appertains to make and use the same.

The invention relates to draft rigging for railway cars, and more particularly to yokes for draft rigging, and the primary object of the invention, broadly stated, is ¹⁵ to provide a simple, strong and reliable yoke which may be constructed of forged steel or wrought metal.

It might be here noted that the yoke herein described and claimed is manufactured by the process which forms the subject of my copending application Serial No. 392,395, filed June 28, 1920.

There are other objects of the invention which will hereinafter appear from the detailed description of the single embodiment of the invention which is herein illustrated on the accompanying drawing, in which,—

Figure 1 is a view in top plan of a yoke embodying my invention.

Fig. 2 is a view in side elevation of the construction shown in Fig. 1.

Fig. 3 is a view in section on the line 3—3, Fig. 2, the direction in which the section is viewed being indicated by the arrow.

Fig. 4 is a like view on line 4—4 of Fig. 2, the arrow indicating the direction of the view.

Throughout the specification and drawing like parts are designated by like reference characters.

The yoke 1 preferably comprises a loop member provided with spaced arms 2, 2 which may be united at their inner ends by a curved bar or section 3 preferably integrally formed with the said arms. Adjacent ⁴⁵ their outer ends each of the said arms is provided with a T-head 4, and to the rear of each T-head I preferably form each arm with an inclined or beveled edge 5, clearly shown in Fig. 1. The outer ends of the T-heads 4 are preferably of greater thickness and may be provided with beveled inner faces 6, 6, best shown in Fig. 3.

To connect the coupler (not shown) to ⁵⁰ the loop member in the conventional man-

ner I combine with the latter a pair of side members 7 which are adapted to be assembled with the said T-heads 4 to form a hooded or box-shaped end in which the rear end of the coupler extends.

Each of the said side members 7 is preferably formed as described in my said copending application, and each comprises an upright web 8 having therein a coupler key receiving slot 9. Each web 8 is preferably ⁶⁰ thickened adjacent the forward end of the slot 9, as shown at 10, to provide additional bearing area for the forward edge of the coupler key as is customary in this form of yoke. Adjacent the inner end each web ⁶⁵ 8 is provided with lateral projections 11, the outer portions of which are thickened and inwardly beveled, as clearly shown at 12 in Fig. 4.

The side members 7 are adapted to lie ⁷⁰ on opposite sides of the upright faces of the arms 2 and to have the projections 11 of the said side members in contact with the inner and rear faces of the said T-heads 4. The side members when in this position are welded to the yoke arms and form therewith a hooded vertical yoke. It should be noted that the strain transmitted to the side members 7 by the outward movement or draft upon the coupler is in turn ⁷⁵ transmitted to the arms 2, and that this strain is resisted not only by the welded connection but by the metal of the interengaged projections on the arms 2 and the side members 7, the said metal being in direct shear.

Having now described my invention, what I claim as new and desire to secure by Letters Patent is:

1. A yoke comprising a loop member having headed ends formed by integral laterally extending portions and a pair of independent side members, each of which is furnished with a pair of laterally extending projections, the projecting portions of said loop member being adapted to overlie the side members and to engage the projections thereof, and means for uniting said loop and side members.

2. A yoke comprising a loop member having headed ends and a pair of side members connected thereto, each arm of the said loop member being provided with oppositely directed outwardly extending portions and said side members each having oppositely

directed inwardly extending portions, the said portions on the side members being adapted to engage behind the projecting portions on the loop member.

3. A draft yoke comprising a loop member furnished with projections adjacent its open end, said projections extending laterally beyond the planes of the side edges of the said loop member, and side members each of which is provided with a key-receiving

slot and each being furnished with upright and laterally extending projections adjacent the inner end thereof, said side members each being adapted to be assembled with the said loop member, the respective projecting portions on said loop member being adapted to engage the adjacent projecting portions of the side members.

In testimony whereof I affix my signature.

B. W. KADEL.
